DESIGN FOR A COMBINED LAPEL WATCH AND PICTURE FRAME

Sol P. Kaufman, New York, N. Y.

Application July 28, 1944, Serial No. 114,604

Term of patent 3½ years

(Cl. D42—8)

To all whom it may concern:

Be it known that I, Sol P. Kaufman, a citizen of the United States, residing at New York city, in the county and State of New York, have invented a new, original, and ornamental Design for a Combined Lapel Watch and Picture Frame, of which the following is a specification, reference being had to the accompanying drawing, forming a part thereof.

Fig. 1 is a front view of a combined lapel watch and picture frame, showing my new design.

Fig. 2 is a side view thereof.

Fig. 3 is a rear view thereof.

The dominant feature of the design resides in the portions shown in full lines.

I claim:

The ornamental design for a combined lapel watch and picture frame, substantially as shown and described.

SOL P. KAUFMAN.
